UNITED STATES PATENT OFFICE.

EARL F. JAGER, OF CHICAGO, ILLINOIS, ASSIGNOR, BY DIRECT AND MESNE ASSIGNMENTS, OF ONE-HALF TO FRANK JAGER, OF DESPLAINES, ILLINOIS, AND ONE-HALF TO ELIZABETH J. SPRY, OF CHICAGO, ILLINOIS.

CAR-DOOR HANGER.

Application filed July 7, 1923. Serial No. 650,006.

This invention pertains in general to sliding doors, and while its principles may be embodied in doors for various structures, the invention as shown here, for purposes of 5 illustration, is embodied in a car door adapted for use on box cars, and the like.

One of the purposes of this invention is to provide a door carrying mechanism whereby the door will be supported upon ball 10 bearings so as to move easily, and the track upon which the balls travel will be protected from the weather so as to preclude an accumulation of snow, sleet, or other foreign matter on the track.

15 Another purpose is to provide a novel spacing member in which the antifriction balls are mounted, and to connect this spacer to the door so that it will be permanently associated with the door, but will 20 be capable of longitudinal sliding movements relatively thereto.

Another and important object is to provide a door carrying mechanism whereby the movement of the door is checked as it 25 approaches the limits of its opening and closing positions.

A further object of this invention is to 30 provide a door carrying mechanism including anti-friction members interposed between the door and its support in which the anti-friction members are connected to the support in a manner which will permit a limited sliding longitudinal movement between the door and said members, this relative 35 movement being checked near the final movements of the door as the same approaches its open or closed position in order to interpose a frictional checking action between the door and support to thereby prevent violent slamming of the door against 40 its stops.

Another feature of the invention resides 45 in improved means for forcing the door inwardly as it approaches the limits of its travel, and for automatically locking the door in both fully opened and fully closed position so as to preclude the same from slamming back and forth when the car is in transit.

50 Other objects and advantages of this invention should be readily appreciated as the

same becomes better understood by reference to the following description, when considered in connection with the accompanying drawings.

55 Referring to the drawings:

Fig. 1 is a fragmentary side elevation of a car equipped with my invention;

Fig. 2 is a detail of one of the door locking devices;

Fig. 3 is a vertical sectional view through the door shown in Fig. 1;

Fig. 4 is a similar view of a modified construction;

Fig. 5 is a top plan view of one of my 65 improved spacers;

Fig. 6 is a side elevation thereof;

Fig. 7 is a view similar to Fig. 5 of a modified form of spacer;

Fig. 8 is a side elevation thereof; and 70

Fig. 9 is an inside view of the supporting track.

Referring to the drawings more in detail, reference character 11 indicates generally the side wall of a car provided with the 75 usual door opening, and the customary front and rear door stops 12 and 13, respectively. A door 14 is adapted to close the door opening, and is mounted to slide back and forth parallel with and outside of the car side 80 wall.

To the lintel 15 of the car there is fixedly attached by bolts 16, or otherwise, a door supporting track, which in the form illustrated in Fig. 3 comprises an angle bar 17, 85 mounted with the horizontal flange projecting inwardly toward the side wall of the car. A similar angle bar 18, providing a hanger, is fixed to the inner face of the door 14, and has its horizontal flange projecting outwardly over the horizontal flange of the track. Between the horizontal flanges of the track and hanger are disposed a plurality of antifriction balls 19, adapted to travel longitudinally of the track and relatively to 90 both the track and hanger as the door is moved back and forth.

These balls are mounted in a spacer, best 95 shown in Figs. 5 and 6, which comprises a bar 21, provided with apertures through 100 which the balls project upwardly, and to the lower face of this hanger a pair of apertured

bracket members 22 are attached, preferably by rivets 23. These brackets are also apertured so that the balls project downwardly to engage the track. It will be apparent, therefore, that the balls are maintained in predetermined spaced relation by this spacer, which travels together with the balls longitudinally of the track, as the door is opened and closed. The door being carried by the balls 19, it will ordinarily move relatively to the spacer at the same rate and in the same direction as the spacer moves relatively to the track.

The spacer bar 21 and the balls 19 are connected to the hanger in a manner which will permit a limited sliding longitudinal movement between the door and said balls. This relative movement is checked, as will be explained, near the final movements of the door as the same approaches its open or closed position, in order to interpose a frictional checking action between the door and track to thereby prevent violent slamming of the door against its stops. To this end the spacer bar 21 is provided between the balls with an elongated slot 24, through which a bolt 25, depending from the horizontal flange 26 of the hanger projects. The head of this bolt being wider than the slot 24, serves to attach the spacer to the hanger, but at the same time a limited amount of sliding movement of the spacer relatively to the hanger is permitted, said bolt being adapted to abut the ends of the slot 24 near the final movements of the door to check such relative movement of the spacer. When the relative movement between the balls and the door is checked, the balls instead of functioning as antifrictional members between the hanger and the track, will introduce a frictional checking action therebetween, resulting in a retardation of the final movements of the door.

In the modified form of spacer illustrated in Figs. 7 and 8, the ends of the spacer bar 27 are turned inwardly, as indicated at 28, providing thereby retainers for the balls, which perform the same function as the retaining bracket 22, previously described.

In order to prevent the spacer and anti-friction balls from riding too far on the track so as to prevent the spacer from being in proper position to permit relative movement with respect to the door when the same is subsequently operated, the horizontal flange of the track 17 is provided as shown in Fig. 9 with upwardly extending projections 30, which, in the present instance, are struck up from the metal of the flange itself. These projections are spaced apart and relatively to the extremities of the door movement so that the spacer is adapted to abut against one of such projections in the path of the spacer whenever there has not been free relative movement between the spacer

and the hanger, as for example, whenever the friction between the bolt 25 and the bar 21 should become so great as to prevent relative movement between the spacer and hanger. Thus, the lugs 30 insure relative movement between the spacer and hanger during an opening or closing movement of the door, and also insure the proper relative position of the spacer with respect to the hanger when the door comes to rest in open or closed position, so that relative movement will be permitted between the spacer and hanger upon a subsequent operation of the door.

At the upper corners of the door, and also intermediate the ends thereof, if desired, there are fixedly secured reinforcing plates 29, which perform the dual function of reinforcing the door and also of preventing the door from contacting with the outer face of the car side wall as the door is moved back and forth. In ordinary car construction the outer face of the side wall is spaced inwardly an inch or more from the outer plane of the door opening, and as will be apparent from Fig. 3, the plates 29 are provided with upward extensions 31, which, when the door is in closed position as shown in Fig. 3, clear the outer face of the track 17. When the door is opened, however, or during its opening and closing movements, inward movement of the upper edge of the door into contact with the opposed side wall of the car is prevented by engagement of these extensions with the outer face of the track, which, therefore, prevent contact between the door and the side wall, and preclude scratching and other injury which would result from such contact.

The lower edge of the door is guided in any suitable manner, and in the present instance it is shown as equipped with a Z-bar 32, the downwardly projecting flange 33 of which is disposed inwardly of guiding brackets 34 by which the lower edge of the door is held in position.

In the modified construction shown in Fig. 4, the track 35 is shaped to extend outwardly beyond, instead of being disposed beneath, the lintel 36. In this instance, also, the hanger 37 is of the same shape as the track, although a hanger similar to that shown in Fig. 3 might be employed with this form of track if desired.

For the purpose of locking the door in both open and closed positions, I have provided automatic locking means comprising front and rear dogs 38 and 39, pivotally mounted adjacent the stops 12 and 13 upon pivot bolts 41 and 42. Each dog is provided intermediate its ends with a vertically disposed slot 43 through which a bolt 44 extends into the door stop. The inner end of each dog is provided with a depending latch 130

45, beveled at its side toward the door so that the outwardly projecting flanges 46, one of which is formed at each end of the door reinforcing bar 47, will lift the dog as the door 5 approaches the limit of its movement, whereupon the latch 45 will ride over the flange and then drop so as to prevent reverse movement of the door. The locking dogs also 10 serve to hold the locked edge of the door against outward movement away from the car structure, and for the purpose of wedging the door toward the car side wall, the inner end of each dog is beveled, as indicated at 48, Fig. 2, so that the door is forced 15 inwardly as it approaches the limit of its travel.

In addition to these locking devices, which are adapted to automatically lock the door in both open or closed positions, the 20 door is preferably equipped with a locking and sealing device, indicated generally by reference character 49 (Fig. 1), by which the car may be locked and sealed to protect the lading. This locking and sealing device may 25 be of any preferred construction, the particular form illustrated being disclosed in a co-pending application.

It is believed that my invention, its preferred construction, and its many advantages 30 will be understood from the foregoing without further description, and obviously, the structural details may be varied within considerable limits, without departing from the spirit of the invention, as defined in the following claims.

I claim:

1. The combination of a supporting track, a sliding door, antifriction balls by which said door is supported from the track, a 40 spacer connecting said balls, said spacer comprising a perforated bar and perforated means for maintaining the balls in engagement with the bar, and a slideable connection between said spacer and the door, permitting relative movement between said spacer and door.

2. The combination of a sliding door, a supporting track, a spacer between the door and track and extending a distance slightly 50 greater than one half the width of the door, said spacer having angular portions near its ends each including a spaced flange, each of said portions having apertures therein in vertical alignment, one of the apertures 55 being in the flange and ball bearings retained in said portions and projecting through the apertures to engage the door and track and give support to the door.

3. The combination of a sliding door, a 60 hanger therefor, a supporting track, anti-friction members by which said door is slideably carried upon said track, a spacer connecting the anti-friction members, said spacer and anti-friction members being interposed between the hanger and track, the

spacer and anti-friction members being adapted for free traveling movement during the greater part of the door movement, means for engaging the spacer and checking the relative movement of the spacer and anti-friction members carried thereby with respect to the door as the door approaches the limit of its opening or closing movement in either direction to thereby convert the anti-friction members into friction members and cushion the final opening or closing movements of the door. 70

4. The combination of a sliding door, a supporting track, a hanger by which said door is suspended from the track, anti-friction balls between said track and said hanger, a spacer connecting said balls, said spacer and anti-friction balls being movable relative to the hanger and track during the greater portion of the door opening or closing movements, abutments carried by the track in the path of movement of the spacer to stop the longitudinal movement of the spacer as the door approaches the limits of its full opening or closing positions to thereby insure relative movement between the spacer and door. 80

5. The combination of a supporting track, a slideable door, a hanger by which said door is suspended from said track, anti-friction balls interposed between said hanger and said track, a spacer connecting said balls, means for slideably connecting said spacer with said hanger, said spacer having a free slideable movement relative to the hanger and track during the greater portion of the opening or closing movements of the door, means for stopping the relative movements of the spacer and anti-friction balls carried thereby with respect to the door when the door approaches its full opening or closing movements, to thereby convert the anti-friction balls into friction devices and cushion the final opening or closing movements of the door. 95

6. The combination of a supporting track, a sliding door, anti-friction balls by which said door is supported from the track, a spacer connecting said balls, said spacer comprising a perforated bar and perforated means for maintaining the balls in engagement with the bar, a slideable connection between the spacer and the door, permitting relative movement between the spacer and the door during the greater portion of the opening or closing movements of the door, means for stopping the relative movement of the spacer with respect to the door to thereby cause the balls to exert a frictional resistance between the door and the track during the continued final closing or opening movements of the door, to thereby check and cushion such final movements of the door. 100

7. The combination of a sliding door, a 110

115

120

125

130

- supporting track therefor, a hanger by which said door is suspended upon the track, said hanger and track being of substantially U-shaped formation and adapted for interfitting relation, to provide a space therebetween, anti-friction balls interposed between said hanger and track and fitting within the space between the track and hanger, a spacer connecting said balls, the spacer and 10 balls being adapted for free relative movement during the greater portion of the door opening, means for stopping the relative longitudinal travel of the spacer and balls with respect to the door as the door approaches its full opening or closing movements, said means upon a continued movement of the door causing a frictional resistance of the balls between the hanger and track to thereby check the final opening and 15 closing movements of the door.
8. The combination of a supporting track, a door, antifriction balls upon which said door is carried by the track, a spacer comprising a longitudinally slotted bar provided with ball receiving perforations, means for preventing displacement of the balls from said perforations, a bolt extending through said slot whereby the spacer is 20 slidably connected to the door, and means 25 for engaging the spacer as the door approaches its full open or closed position to change the relative movement of the spacer with respect to the door to thereby cause 30 the balls to introduce a frictional resistance between the track and door. 35
9. The combination of a sliding door, a supporting track, a longitudinal member by which the door is connected to the track, antifriction means by which said door is slidably carried upon said track, said means 40 being interposed between said member and track, said means being adapted for free traveling movement during the greater part of the door movement, means for engaging said first means and changing the relative 45 movement thereof with respect to said member as the door approaches the limit of its opening or closing movement in either direction to thereby convert the antifriction means into a friction means and cushion 50 the final opening or closing movements of the door. 55
10. The combination of a sliding door, a supporting track, a longitudinal member by which said door is connected to the track, antifriction means between said track and member, said means being movable relative to said member and track during a greater part of the door opening or closing movement, and abutments carried by the track in 60 the path of movement of said means to stop the longitudinal movement thereof after the door approaches the limits of its opening or closing positions to thereby insure relative movement between said means and door. 65

EARL F. JAGER.
